[57] CLAIM

The ornamental design for a spout, as shown and described.

DESCRIPTION

FIG. 1 is a left side elevational view of a spout showing my new design, the right side being a mirror image of the left side shown;

FIG. 2 is a top plan view thereof;

FIG. 3 is a front elevational view thereof;

FIG. 4 is a rear elevational view thereof; and

FIG. 5 is a perspective view taken from the top, front and left side thereof.

FIG. 1

FIG. 3

FIG. 4

FIG. 5

FIG. 2
